UNITED STATES PATENT OFFICE

RUDOLF ROESE, OF BERLIN-FRIEDENAU, GERMANY

DOUBLE SLIDING WINDOW

Application filed July 11, 1929, Serial No. 377,520, and in Germany July 16, 1928.

The object of the present invention is to provide a double sliding window without counter-weights having wedge-shaped joints, the sash frames of which are connected to one another by means of ropes passing over rollers.

The invention consists in that the lower edge of the inner sliding sash frame is pivotally connected to an end-board vertically movable in the sides of the window frame to which also the ropes are fastened which, contrary to the present practice, are passed not only in an upward but also in a downward direction over upper and lower rollers respectively and whose ends are attached to the bearings on which the outer sliding sash frame is pivotally mounted, the sliding sash frames may be fixed in their closed or an intermediate position by means of a window board which may be moved at a right angle to and within the sides of the window frame.

Another feature of the invention lies in the special arrangement of the wedge-shaped members on the inner longitudinal surfaces of the sliding sash frames for the purpose of tightening the window.

The annexed drawings show, by way of example, one embodiment of the invention. In these drawings

Figure 1 is a longitudinal section of the partly opened sliding window (ventilating position).

Figure 2 is a longitudinal section of the sliding window with the sashes in tilted position.

Figure 3 is a cross section of the window frame and the sash-frame at a point intermediate the transom and window board.

Figure 4 is a cross section of the window frame at a point below the window board.

The lower edge of the inner sliding sash frame 2 is pivotally connected to an end-board 29 movable in vertical direction within the sides 6 of the window frame. To this end-board 29 also the ropes 37 are fastened which in contradistinction to the present practice are passed over rollers 36 not only in an upward but also in a downward direction and have their ends attached to the bearings 39 of the outer sliding sash frame 3.

By this arrangement the outer sliding sash frame 3 in closing the window is positively pulled into its closed position and both sliding sash frames may be tilted without difficulty.

In order to get the parts of the window tightly fitting also in lateral direction, particularly the outer sliding sash frame 3, and in order to avoid the rattling of the sashes in windy weather, the wedges 41, 42 are provided on the inner longitudinal surfaces of the sliding sash frames 2 and 3 and at about the middle thereof. By closing the window the said wedges are brought into overlaying engagement, thus forcing the outer sliding sash frame 3 firmly upon its rebate.

By means of the window board 33 which may be moved at a right angle to and within the sides 6 of the window frame the sliding sash frames are being fixed in their closed as well as any intermediate position by means of suitable stops. The window board 33 in its closing position is in tight engagement with the lower edge of the end-board 29 forming at the same time a support for the sliding sash frame 2 thus saving the ropes.

What I claim is:

1. In a double sliding window, a window frame having side portions, inner and outer sash frames, an end-board slidably mounted in the sides of the window frame and pivotally mounting the inner sash frame, a bearing pivotally mounting the outer sash frame, a rope connecting the inner and outer sash frames, and pulleys arranged above and below said frames supporting said rope, and a window board mounted in the window frame for movement perpendicularly to the sliding movement of the sash frames for retaining the latter in adjusted positions.

2. A window construction as claimed in claim 1, characterized by the provision of wedge-shaped elements carried by the inner and outer sash frames midway the height of the latter adapted to mutually engage one another when the sash frames are moved to closed position.

In testimony whereof I affix my signature.

RUDOLF ROESE.
